(57) **CLAIM**

The ornamental design for a spare tire cover, as shown and described.

DESCRIPTION

FIG. 1 is a front elevation view of a spare tire cover

FIG. 2 is a left side perspective view of a spare tire cover

FIG. 3 is a right side perspective view of a spare tire cover

FIG. 4 is a top plan view of a spare tire cover

FIG. 5 is a bottom plan view of a spare tire cover; and,

FIG. 6 is a rear plan view of a spare tire cover.

The broken lines showing of the tire wheel rim is included for the purpose of illustrating environmental subject matter and forms no part of the claimed design.
